C. T. JENEWEIN & C. W. DOBELIN.
BOX COVER FASTENING.
APPLICATION FILED DEO. 6, 1912.

1,064,653.

Patented June 10, 1913.

UNITED STATES PATENT OFFICE.

CHARLES T. JENEWEIN, OF BLACKHAWK, AND CHARLES W. DOBELIN, OF MADISON,
WISCONSIN.

BOX-COVER FASTENING.

1,064,653.

Specification of Letters Patent. Patented June 10, 1913.

Application filed December 6, 1912. Serial No. 735,288.

To all whom it may concern:

Be it known that we, CHARLES T. JENEWEIN and CHARLES W. DOBELIN, citizens of the United States, and residents, respectively, of Blackhawk, in the county of Sauk and State of Wisconsin, and Madison, in the county of Dane and State of Wisconsin, have invented a new Box-Cover Fastening, of which the following is a specification.

10 Our invention is an improvement in the class of devices for securing lids or covers of boxes without the aid of nails or screws, a metal keeper being hinged to one end of the box body and provided with means for 15 securing it in closed position after the cover has been put in place.

The details of construction, arrangement, and combination of the parts embodying our invention are as hereinafter described, 20 and illustrated in the accompanying drawing, in which—

Figure 1 is a perspective view of a box provided with our cover fastening arranged in the closed position. Fig. 2 is a longitudinal section of the same. Fig. 3 is a detail section on the line 3—3 of Fig. 1. Fig. 4 is a detail perspective illustrating the adjustment of the hinged keeper when applying or removing a cover.

30 In the several views, 1 indicates the body and 2 the flat cover of a rectangular box or case. A metal keeper or socket 3 for the cover is preferably attached by nails, screws, or rivets to one end and upper angle 35 of the body 1 and projects above the latter sufficiently to adapt it to receive one corner of the cover, as shown in Figs. 1 and 2. Another metal keeper or socket 4 is applied to the other end and upper angle of the box body 1 and provided with downwardly extended ears which are pivoted to the sides of the body at 5, so that the keeper may be 40 swung on or off the cover 2, as illustrated in Fig. 4, which movement is required both in applying the cover and detaching it.

In other words, when the hinged keeper 4 is thrown back into the position indicated in Fig. 4, the cover 2 may be applied by slipping its opposite end under the fixed keeper 3, and then, when the cover is flat 50 on the body 1, the hinged keeper 4 may be swung back into place, as indicated in Figs. 1 and 2. For holding the hinged keeper 4 in this engaging position, we employ a turn-button 6, the same being pivoted on 55 the end of the box body 1 and made of such length that, when turned up as shown in Figs. 1 and 2, its free end extends over and presses upon the adjacent edge of the keeper 4. It is obvious that the adjustment of this 60 device 6, for securing or releasing the keeper 4, may be very easily and quickly made.

To prevent the button 6 from becoming accidentally detached from the keeper, the latter is provided with slight projections 7, 65 preferably formed by striking up the metal forming the body of the keeper. It will be understood that the locking device 6 has sufficient resiliency to allow it to be pushed over either of the projections 7, and, when 70 once in place between the two, it is not liable to be accidentally displaced.

When duly applied, as shown in Figs. 1 and 2, the cover is held securely both as to endwise and lateral movement.

75 It will be seen that by means of our invention, a cover 2 may be used indefinitely, since it is subject to no injury in attachment or detachment, and that it may be applied or removed much more quickly than a cover 80 which requires nails, screws, or other analogous means for fastening.

We provide for sealing the cover, as shown in Figs. 1 and 3, where a wire 8 is passed through one end of the hinged 85 keeper 4 and through the adjacent portions of the box body and cover, and then a lead, or other soft-metal seal 9 is applied to the ends of the wire in a well known manner.

It is to be understood that our invention 90

is applicable to boxes and cases of various forms and materials, for instance, whether made of metal or wood or a fiber composition.

5 What we claim is:—

The combination with a box body and cover, of a keeper constructed of metal and pivoted to one end and upper angle of the body, so that when swung up into vertical position the keeper projects over and receives the end of the cover, and a turn-button pivoted below the keeper and adapted

to engage the same when adjusted in a vertical position, as described.
